UNITED STATES PATENT OFFICE.

WILLIAM HENRY MILLER, OF GALVESTON, TEXAS.

SHEET-METAL FIREPROOF WINDOW.

No. 810,663.

Specification of Letters Patent.

Patented Jan. 28, 1906.

Application filed April 17, 1905. Serial No. 265,996.

To all whom it may concern:

Be it known that I, WILLIAM HENRY MILLER, a citizen of the United States, residing at Galveston, in the county of Galveston and State of Texas, have invented certain new and useful Improvements in Sheet-Metal Fireproof Windows; and I do hereby declare the following to be a full, clear, and exact description of the invention, such as will enable others skilled in the art to which it appertains to make and use the same.

My invention relates to improvements in window construction; and its object is to provide a fireproof window particularly adapted for use in fireproof structures and having its frame and sash formed of sheet-metal portions assembled in a novel manner.

Another object is to provide sashes of this construction which can be opened and held in such position, but which will automatically close when air of an unusually high temperature comes in contact with them.

A still further object is to so arrange the sashes within their frame as to permit them to be readily moved from or placed into position.

With the above and other objects in view the invention consists of a window-frame, the sides, top, and bottom of which are each formed of strips of sheet metal of proper shape and permanently connected with rivets and lock-joints. The frame has grooves formed within it for the reception of supporting-pins extending laterally from the upper sash, whereby said sash is adapted to be swung into either upright or horizontal position.

The invention also consists in providing a lower sash with counterbalances, which are secured to said sash by fusible devices which extend to opposite sides of the sash, so as to be readily contacted by any gases of an unusually high temperature, thereby causing the sash to be released and to drop by gravity into closed position.

The invention also consists in providing means whereby the lower sash may be cushioned when falling into closed position.

The invention also consists of a fusible holder for securing the upper sash in a horizontal position, said holder being adapted to release said sash when heated, so as to cause it to automatically close.

The invention also consists of certain other novel features of construction, which will be

hereinafter more fully described, and pointed out in the claims.

In the accompanying drawings I have shown the preferred form of my invention.

In said drawings, Figure 1 is a perspective view of a window constructed in accordance with my invention. Fig. 2 is a central vertical section therethrough. Fig. 3 is a vertical section through the frame and window-sashes, taken at one side of the center thereof to show the fusible link in elevation. Fig. 4 is an enlarged section on line 4-4, Fig. 3. Fig. 5 is a side elevation of a portion of the lower sash and showing the means for connecting the chain of the counterbalance to the sash. Fig. 6 is a perspective view of a portion of one side of the upper sash and showing the pivot-pin thereof. Fig. 7 is a central vertical section through the parts shown in Fig. 6. Fig. 8 is a perspective view of a portion of the inner face of the frame and showing the bearing for the pin disclosed in Fig. 6. Fig. 9 is a perspective view of a portion of one of the rails of a sash, showing the glass-holding means prior to placing the glass within the sash. Fig. 10 is a section through the parts shown in Fig. 9 and showing the manner of securing the glass in position by bending the holding device, and Fig. 11 is a section through an intermediate bar of a window-sash constructed in accordance with my invention and showing the means for securing the glass thereto.

Referring to the figures by numerals of reference, 1 is the inner strip of one side of the window-frame and is formed of a continuous length of sheet metal extending from the sill to the top of the frame. This strip is stepped upon its inner face to form an angular shoulder 2, which forms one wall of a guideway for the lower sash within the casing. The other wall of this guideway is formed of a channeled strip 3, having key-hole-slots 4 therein, which receive and engage screw-bolts 5, secured to the strip 1. It will be understood that by raising the guide-strip 3 so as to bring the large portions of the slots 4 around the bolts 5 said guide-strip can be readily removed, and when it is in its normal position with the screw-bolts in the contacted portions of slots 4 it is impossible for it to become accidentally displaced. A lateral extension 6 is formed along one edge of the face-strip 1, while the other edge thereof has a lateral-extending channeled portion 7.

2

This channeled portion is adapted to receive one edge of the outer strip 8 of the side of the frame, while the extension 6 engages the opposite inwardly-bent edge 9 of the strip 8. 5 The two sides of the window-frame are formed as herein described, and each has an opening 10 adjacent the bottom thereof and between the shoulder 2 and the outer face of the frame. These openings are normally closed by plates 10, adapted to be secured in position by means of screw-bolts 12 or in any other suitable manner. By removing these plates access may be readily had to the interiors of the side portions of the window-frame. These side portions are permanently connected to the sill and top of the window-frame in any preferred manner, preferably by forming lugs 13 upon the ends of the strips which project into the sill and head, as shown by dotted lines in Fig. 15, and are adapted to be subsequently bent upward so as to bind all portions of the frame together. The sill is formed of a single strip 14 of sheet metal, which is open at the bottom and the upper surface of which is stepped 20 and inclined so as to simulate the sill of the ordinary wooden window-casing. The top of the frame is formed, preferably, of two strips 15 and 16, which interlock by forming the strip 15 with channeled edges 17, in 25 which are seated the edges of the strip 16. The outer strip 16 is substantially the same in contour as the strips 8, and the inner strip 15 is the same in contour as the strips 1, excepting that it is provided with a bead 18, adapted to 30 register with stop-strips 19, secured longitudinally to the inner strips 1 adjacent the outer edges thereof. These stop-strips 19 extend downward to points adjacent the ends of grooves 20, which are formed within the strips 1. These grooves are inclined downward from the shoulders 2 and register with boxes 21, which are riveted or otherwise permanently connected to the strips 1 and upon the inner surface thereof. Another stop-strip 22 is secured to strip 1 adjacent the shoulders 2 and below the grooves 20, and the lower ends of these stop-strips are connected by an intermediate cross-bar 23, formed of a base-strip 24, having inwardly-bent edges 25, which interlock with the recurved edges 26 of an upper strip 27. This 45 upper strip has a bead 28 along the inner edge thereof, which registers with the stop-strips 22. 50 The slots or grooves 20, before referred to, are adapted to receive bearing-pins 29, formed upon plates 30, which are secured within the sides of the upper window-sash 31. This sash consists of an outer strip 32, formed 55 of sheet metal and having inwardly-curved edges 33, adapted to engage the recurved edges 34 of a strip 35, which is bent to simulate the corresponding portion of the ordinary window-sash. This strip 35 has a centrally-arranged shoulder 36, against which

the glass 37 is adapted to be held by means of pliable cleats 38, which are riveted to the strip 35 and are adapted to be bent over the edges of the glass, as shown in Fig. 10. The plate 30 is secured to the inner surface of the side strips 32 by means of screw-bolts 39, which extend through slots 40 within said side strips 32. The bearing-pins 29 also extend through slots, and it will therefore be seen that these pins can be adjusted longitudinally of the sides of the sash. The sash is so proportioned that when it is in a vertical position it will rest between the two pairs of stop-strips 19 and 22 and its lower surface will contact with the top strip 27 of the intermediate bar 23. A spring-catch 41 is secured to the upper bar of the upper sash and is adapted to automatically engage the top of the window-frame, as shown in Fig. 2. This spring-catch has a hook 42, adapted to be engaged by one end of a rod 43, detachably connected to one side of the window-frame. A fusible link 44 is connected to the top bar of the upper sash at a point removed from the center thereof and is adapted to be engaged by the rod 43, which when in such position will hold the sash horizontally and in contact with the adjoining ends of the stop-strips 19 and 22, as shown in Fig. 3.

The lower sash is substantially similar in construction to the upper sash, but the length thereof is greater than the distance between the top of the frame and the intermediate bar 23. The side strips 32 of this lower sash are, however, provided with elongated apertures 45, and openings are formed within the lower portions of the inner and outer face of this sash for the reception of metal tips 46, which are secured to the sash by fusible metal and to which are connected sash chains or cords 47, disposed within the sash. Each of these cords extends over a pulley 48, located within the sash and having a chain 49 extending from it and over a pulley 50 in a portion of the frame. Each of these chains 100 49 has a counterbalance (not shown) connected to it and movable longitudinally within the sides of the frame. The thickness of each of the metal tips 46 is greater than the opening through the pulley-block 48 in 105 which the cord 47 works, and it will therefore be seen that should either of these tips be released it could not pass through or out of engagement with the pulley, but would act as a stop to prevent the withdrawal of the 110 cord therefrom. It will of course be understood that a chain 49 is arranged in each side of the lower sash, and therefore two cords 47 are employed, one adjacent each side of the 115 sash.

120 It is thought that the operation of the sashes will be understood from the foregoing description. However it might be stated that the lower sash can be raised or lowered as ordinarily; but when raised the lower rail 125

thereof will always be below the intermediate bar 23, so that the ends of the tips 46 will always be exposed to the action of heat. The upper sash can be swung into a horizontal position by pulling on the catch 41 by means of rod 43, and after it has been released it can be held in a horizontal position by placing the rod in engagement with link 44. If both sashes are opened, as shown in Fig. 3, they will remain so unless link 44 and one or both of the tips 46 are subjected to unusual heat. In that event both the link and the tips will fuse. This action of the link will cause the rod 43 to become disengaged from the upper sash, and said sash will swing by gravity into closed position. If one of each of said tips 46 should be fused, they would promptly release the ends of the cords 47, connected thereto, and the weight of the sash would cause it to fall by gravity into a closed position. When it reaches this point, the released tips will contact with the pulleys 48 and prevent displacement of the cords 47. The passage of the cords over their pulleys 48 will sufficiently retard the falling sash to prevent it from dropping with sufficient force to become injured.

It will be seen that either or both of the sashes can be readily removed. The upper sash need only be inclined so that its bearing-pins 29 can be slid from the slots 20. To remove the lower sash, the guide-strips 3 are slid upward until the bolts 5 are brought within the large ends of the slots 4. After the lower sash has been removed in this manner the cords 47 can be drawn down and tips 46 attached again by means of fusible metal without the necessity of taking the sash to pieces, because the openings 45 permit access to be readily had to the interior of the sash.

Where intermediate rails are formed within the sash, I preferably construct them in the manner shown in Fig. 11. By referring to said figure it will be seen that said rail is formed of a main strip having an intermediate bead 51, from which project oppositely-extending flanges 52, terminating with converging edges 53. These edges and flanges are overlapped by a base-strip 54, which also extends over and serves to retain the pliable cleats, which are similar to the cleats 38 and are adapted to hold the glass in position. The glass used in connection with the sash is preferably wired, and after it has been secured in place by means of the cleats 48 and 54 putty can be placed over said cleats, so as to give the sash the ordinary appearance. I have shown putty so arranged at 56 in Figs. 3 and 4.

A window such as herein described is light, durable, and wind, rain, and fire proof and is particularly adapted for use in fire-proof structures. The fact that the windows will automatically close in the event of a fire

is also considered by me to be an important feature of the invention.

As shown in the drawings, a suitable sash-lock 57 can be connected to the sash and the sliding sash is preferably provided with one or more sash-lifts 58.

In the foregoing description I have shown the preferred form of my invention; but I do not limit myself thereto, as I am aware that modifications may be made therein without departing from the spirit or sacrificing the advantages thereof, and I therefore reserve the right to make such changes as fairly fall within the scope of my invention.

Having thus fully described my invention, what I claim as new, and desire to secure by Letters Patent, is—

1. The combination with a metallic window-frame comprising interlocking inner and outer strips, of slots within the sides of the frame, boxes in said frame registering with and closing the slots, a swinging sash within the frame, and bearing-pins adjustably connected thereto and detachably mounted within the slots and boxes.

2. The combination with a window-frame formed of interlocking metallic strips and normally closed apertures in the sides of the casing, said sides having guide-shoulders; of a detachable guide-strip parallel with the shoulder, a metallic sash slidably mounted between the strip and shoulder, a counterbalance, a flexible device extending from the counterbalance through the frame and into the sash, a pulley within the sash and connected to said device, a non-fusible cord mounted upon the pulley and fusible connections between the ends of the cord and the sash, said connections extending through the walls of the sash.

3. The combination with a window-frame comprising interlocking metallic strips and longitudinally-extending shoulders formed by the sides of the frame upon the inner surfaces thereof, of an intermediate metallic cross-bar connecting the sides of the frame, a stop-bead integral therewith, stop-strips upon the sides of the frame alining with said bead, a bead upon the top of the frame and depending therefrom, stop-strips upon the side of the frame alining with said bead, a sash pivoted within the frame between the stop-strips and adapted to contact therewith when opened or closed, and bearing-pins adjustably connected to the sash and engaging the frame.

4. The combination with a window-frame, of a sash movably mounted therein and formed of interlocking metallic strips constituting side and end bars, a pulley within each of the side bars, a counterbalance within the frame, flexible devices connecting the counterbalance and pulleys, non-fusible cords mounted upon the pulleys and within the sash, fusible tips connecting the ends of the

- cords to the sash, said tips extending through the walls of the sash, each tip being of greater thickness than the opening through the pulley.
5. The combination with a window-frame, of a sash movably mounted within the frame, a counterbalance therefor, a fusible connection between the counterbalance and sash, and means for retarding the movement of the sash subsequent to its release from the counterbalance.
6. A window-sash comprising outer and inner interlocking metallic strips forming hollow side and end bars, said side bars having elongated apertures therein, fusible tips extending through the front and rear walls of the bars, a pulley within each side bar, a non-fusible cord mounted upon the pulley and secured at its ends to the tips, said tips being of greater thickness than the diameter of the passage through the pulley to constitute stops.
7. The combination with a window-frame; of a sash movably mounted within the frame, a counterbalance therefor, and a fusible connection between the counterbalance and sash, said connection being disposed upon one outside face of the sash.
8. The combination with a window-frame; of a sash movably mounted within the frame, a counterbalance therefor, and fusible connections between the counterbalance and sash, said connections being disposed upon opposite outer faces of the sash.
9. The combination with a metallic window-frame; of a swinging metallic sash mounted within the window-frame, a sliding sash within the frame, independent means for holding both of the sashes in opened position, and fusible connections between said means and their respective sashes, said connections being disposed outside of the sashes.
- In testimony whereof I have signed my name to this specification in the presence of two subscribing witnesses.

WILLIAM HENRY MILLER.
